(57) **CLAIM**

The ornamental design for a magnetic fastener unit, as shown and described.

DESCRIPTION

FIG. 1 is a bottom isometric view of the male fastener and the female fastener of an exploded magnetic fastener unit in their separated or detached position with female fastener member overlying the male fastener member.

FIG. 2 is a bottom isometric view of the male fastener and the female fastener of the magnetic fastener unit of FIG. 1 in their attracted or fastened position;

FIG. 3 is a top isometric view of the male fastener and the female fastener of an exploded magnetic fastener unit in their separated or detached position with the female member overlying the male fastener member; and,

FIG. 4 is a top isometric view of the male fastener and the female fastener of the magnetic fastener unit of FIG. 3 in their attracted or fastened position.
